UNITED STATES PATENT OFFICE.

ROWLAND FOLGER, OF MILFORD, MASSACHUSETTS.

DIVIDERS.

SPECIFICATION forming part of Letters Patent No. 297,979, dated May 6, 1884.

Application filed March 1, 1884. (Model.)

To all whom it may concern:

Be it known that I, ROWLAND FOLGER, of Milford, in the county of Worcester and State of Massachusetts, have invented new and useful Improvements in Dividers, of which the following is a specification.

In the accompanying drawings, in which similar letters of reference indicate like parts, Figure 1 is a perspective view of a pair of dividers embodying my invention. Fig. 2 is a rear elevation of the same.

A and A' represent the legs of the dividers, hinged at *a* and provided with the curved adjusting and retaining bar B, slotted at *b*, adjusted by means of the thumb-screw *d*, and pivoted to the leg A', near the upper end thereof, at *e*. The leg A is scaled for degrees at A'', the numerals thereof ranging from 1 to 90, inclusive. The objects of curving the adjusting-bar B and of pivoting it to the leg A' at a point so near the joint *a* are, first, to enable the said adjusting-bar to be out of the way by sliding near the joint *a* when the dividers are spread, especially between the angles of forty-five and ninety degrees, thus facilitating the use of the same in connection with uneven surfaces, corners, &c.; and, second, by means of the thumb-screw *d*, placed relatively low on the leg A, and extending through the slot *b*, to enable the lower end of said adjusting device, which is squared, (see B'), to move over and substantially on a line with the degree-scale A'', so that the angle of the legs is always indicated by the degree in the scale next the end B'. The outer surfaces of the legs are scaled for inches, the combined length of the two, when spread so as to be on a line, being preferably an exact foot. Each of the legs is hollow or tubular, and is provided with a longitudinal slot, C, a sliding cup or socket, D,

and a thumb-screw or set-screw, E, secured to said socket, by means of which the latter is held in any position in the leg and prevented from dropping out of the same and becoming mislaid. These sockets are adapted to hold 45 pointers *f*, pencils *g*, crayons, lining-pens, brushes, &c., as desired. When pencils *g* or other fragile articles are used, they can, when not in use, be slid up into the tubular leg by means of the sliding socket D, and held wholly 50 inside by the set-screw E, so that their points are protected from injury. The pointers *f* are ground off at their lower ends on their outer sides as they lie in the legs, so that the points are on the inner sides thereof, and when the 55 legs are placed together the two points above named will nearly touch, the advantage of which is apparent to any draftsman. The lower ends, A'', of the legs are tapered, as shown, to facilitate this result. 60

Having thus fully described my invention, what I claim, and desire to secure by Letters Patent, is—

1. In combination with the legs A and A' of a pair of dividers, the curved slotted retaining or adjusting bar B, pivoted at one end to the leg A' relatively near the joint, and adjustably secured by means of its slot to the leg A, at a greater distance from the joint, substantially as and for the purpose set forth. 65

2. The combination of the leg A', the adjusting or retaining bar B, pivoted at *e* thereto, and the leg A, provided with the adjusting-screw *d* and the degree-scale A'', substantially as and for the purpose described. 70

ROWLAND FOLGER.
